UNITED STATES PATENT OFFICE.

OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

MULTIPLE-ZERO ESCAPEMENT MECHANISM.

1,143,240.

Specification of Letters Patent. Patented June 15, 1915.

Application filed July 11, 1912. Serial No. 768,859.

To all whom it may concern:

Be it known that I, OTTO THIEME, a citizen of the United States, residing at St. Louis, Missouri, have invented a certain new and useful Improvement in Multiple-Zero Escapement Mechanism, of which the following is a full, clear, and exact description, such as will enable others skilled in the art to which it appertains to make and use 10 the same, reference being had to the accompanying drawings, forming part of this specification, in which—

Figure 1 is a plan view showing the key board arrangement of a calculating machine 15 provided with my improved escapement mechanism. Fig. 2 is a side elevational view partly in section illustrating the upper portion of the escapement mechanism and the manner in which it coöperates with 20 the zero pins of the traveling carriage. Fig. 3 is a detail view of the restoring bar for the digit pins in the traveling carriage. Fig. 4 is a rear elevational view partly in section illustrating the means for restoring 25 the zero pins in the traveling carriage. Fig. 5 is a side elevational view partly in section as seen from the right hand side of the machine. Fig. 6 is a front elevational view. Fig. 7 is a detail view of the pallets which 30 coöperate with the escapement teeth. Fig. 8 is a detail view of the fixed pallet. Fig. 9 is a detail view of the key operated stops which fix the position of the multiple zero 35 mechanism. Fig. 10 is a front elevational view showing the escapement used as a single-step mechanism. Fig. 11 is a side elevational view of such single-step mechanism. Fig. 12 is a detail view of the pallets and escapement teeth employed in the 40 single-step mechanism. Fig. 13 is a diagrammatic view of the multiple zero mechanism.

This invention relates to a new and useful improvement in escapement mechanisms for 45 calculating machines such as disclosed in Belgian Patent No. 202,081, dated August 21, 1907, French Patent No. 383,719, dated January 16, 1908, and mentioned in application Serial No. 310,739, filed by Hubert Hopkins in the United States Patent Office on or about April 9, 1906, although it is obvious that my present improvement may be used in connection with other types of calculating machines.

55 The object of this present invention is to

provide a simple and efficient escapement mechanism for the laterally movable carriages of calculating machines and one which is not susceptible to over-throw or displacement.

Another object is to provide means whereby a laterally movable carriage may be stepped leftwardly two or more spaces upon the operation of the single key by means of novel mechanism hereinafter described for the purpose of introducing two or more zeros in the machine.

In the drawings, 1 represents the base of the machine.

2 are the key bars identified with the calculating machine pivoted at 3 and on whose forward ends are heads marked with numerals from 1 to 9 inclusive. The rear ends of these key bars 2 lie under vertically movable bars 56 arranged in longitudinal rows 75 and whose upper ends are designed to position setting up pins 63 arranged in a laterally movable carriage 57 traveling in pivoted track bars 58. When the pins 63 are positioned by the keys and the carriage 80 stepped leftwardly, said carriage is lifted. The positioned pin 63 will raise stop pins 93 in front of shoulders 101 on the rack bars 100. As the handle of the machine, not shown, is pulled forward, the racks 100 will 85 move under the impelling action of springs 103 connected to bars 102 having a slot and pin connection with said racks, said forward movement being permitted by the restoring bar 104. When the handle reaches 90 its forward position, either set of accumulating wheels 119 or 268 may be engaged with the racks 100, the rearward movement of the handle causing the bar 104 to engage the levers 102 and restore all of the racks 95 100 rotating the wheels 119 or 268 the distance proportionate to the forward movement of the racks. To take a total, the "T" key is depressed to engage wheels 119 with the racks before said racks start to move 100 forwardly, or the "P" key is operated to engage the wheels 268 with the racks before said racks start to move forward and upon the forward pull of the handle, the racks 100 will move forwardly until the wheels 105 119 or 268 reach their zero position, in which type, not shown, carried by the racks 100, are properly positioned in the printing line to print the total. All of these particulars are fully described in the patent and 110

application before referred to, to which attention is directed for a full explanation of the details of construction and modes of operation which form no part of my present invention. As described in said patent, there is a spring, not shown in the accompanying drawings, for drawing the carriage 57 leftwardly. In said patent, the carriage 57 was provided with a rack 78 with which a segment 77 mounted on the upper end of a shaft 76 coöperated, the lower end of said shaft carrying a segment 205 meshing with a rack 197 whereby the carriage was restored to its normal or right hand position either from the main shaft of the machine or by the error key 206. I employ the same construction here, but instead of having a segmental escapement wheel on the shaft 76, the pallets of which are operated by the key bars 2, I provide a series of escapement teeth 4 on the carriage with which coöperates a rigid pallet 5 in the form of a bent projection on the upper end of a bar 6 and a pivoted or movable pallet 7 on the end of a lever 8 pivotally mounted on the track bar 58 in which the traveling carriage 57 operates. The pallet lever 8 is provided with a pin 9 with which coöperates a spring 10, the lower end of said spring being connected to a plate 11 fixed to the framing of the machine, said plate also forming a bearing for the upper end of shaft 76. The bar 6 is broadened at its lower end so as to lie over all of the digit keys and also the zero key in the single-step escapement, shown in Figs. 10 to 12 inclusive, so that whenever any key bar 2 is operated, the bar 6 will be raised, placing the fixed pallet 5 behind an escapement tooth, and raising the pallet 7 above the tooth which it formerly engaged, permitting the carriage to move leftwardly a short distance so that when bar 6 is depressed to disengage the fixed pallet from this tooth, the spring 10 will draw the movable pallet 7 in front of the next adjacent tooth, thus enabling the carriage to step leftwardly as the operating key rises. A spring 12 is connected to the bar 6 to lower the same. All of the key bars 2 are notched adjacent to the lower broadened edge of bar 6, as shown in Fig. 11, whereby when the lower end of bar 6 is drawn forwardly by means of a rod 13, the lower edge of said bar 6 is brought into registration with said notches and hence the key bars 2 may be operated without operating the escapement. The rod 13 is intended to be connected to the "D" or "Decimal" key in said patent aforesaid and to enable the lower end of bar 6 to be thus pulled forwardly, the bracket 14, which acts as a guide therefor is made movable.

In setting up examples in a ten-key machine, according to the mechanism just above described, if it was desired to introduce an

item containing a number of zeros or ciphers, say for instance—\$50.00, the 5-key would be first operated and then the zero key would be operated three times.

My present invention contemplates a number of multiple zero keys so that the zero setting up pins 63 in the traveling carriage may be positioned by a single key operation to set up two or more zeros according to the number desired. In the example given, the 5-key would be pressed and the three multiple zero key operated once instead of operating the one-zero key three times. With a slight modification of the parts described above and by the addition of other parts, I am able to utilize the above mechanism for multiple zero work.

Referring to Fig. 1, it will be seen that the zero key bars 15', 15'', 15''' and 15'''' are each provided at their forward ends with heads bearing the characters 0₁ 0₂ 0₃ 0₄ respectively. While I have illustrated the mechanism as being limited to the introduction of four zeros into the machine by a single key operation, it is obvious that five or more zeros could be introduced by a single key operation by the addition of appropriate parts. The multiple key bars are pivoted at 3 to the base of the machine and the single zero key bar 15' extends rearwardly and has its end located under the zero bar 56' so as to raise the zero setting up pin 63' in the usual way. It will be noted by referring to Fig. 2 that this zero setting up pin does not have a locking shoulder at its upper end, but is provided with a retaining projection 63^a having both edges beveled so that it is unnecessary to move this pin laterally and downwardly to restore it by means of the restoring bar 68 as contemplated in said patent. The zero setting up pins 63', there being one pin for each longitudinal row of setting up pins, are each provided with an elongated rearwardly extending foot 63^b and as these pins are raised, said foot portions are lifted above an L-shaped plate 16 secured to the rear track bar 58 so that when the carriage travels leftwardly, the zero setting up pins will be moved over the horizontal portion of the plate and locked in their elevated position. Each of the key bars 15', 15'', 15''', and 15'''' has its rear end arranged under bars 56', 56'', 56''' and 56'''' respectively mounted for vertical movement similar to the bars 56 but having extensions at their upper ends whose upper faces are of different widths (see Fig. 13) which are designed to embrace one, two, three and four zero setting up pins respectively depending upon the bar operated. Should any of these bars 56', 56'', 56''', 56'''' be operated, they will, through the bar 6, first raise the fixed escapement pawl 5 on the downward movement of the key head and lift from one to four zero setting up

pins depending upon the zero key operated, and when the zero key is released the movable pallet 7 will be brought into control with the next, the second, the third, or the fourth escapement tooth so that the carriage will, after the zero setting up pin, or pins, have been raised, be stepped over from one to four spaces accordingly.

In Fig. 13, I have conventionally illustrated the different zero setting up pins to the right of the stop pins 93 which is the normal position of the carriage. It is of course obvious that any of the zero pins 63', which may be raised before the digit pin 63, is raised, will be non-significant. However, suppose that the digit pin 63, shown in Fig. 13, was raised by the operation of the "1" digit key, the carriage would be stepped leftwardly placing the raised digit pin in control of the rack in the units column. If it was now desired to place the raised digit pin 63 in control of the "tens", "hundreds", "thousands", or "ten-thousands" column, and at the same time raise the "1", "2", "3", or "4" zero pins 63', the proper zero key would be operated requiring the depression of a single key to raise the one or more zero pins.

The means for variably or differentially spacing the carriage leftwardly consists of a lever 16 pivoted on a suitable bracket secured to the base of the machine and having one end lying over the rear ends of bars 15'', 15''', and 15''''. This lever is notched at the upper edge of that portion which extends over the bars 15'', etc. for the purpose of differentially engaging stop plates 17 and 18 pivotally mounted at their lower ends to bracket extensions secured to the base 1 and provided at their upper ends with forwardly projecting portions which are designed to be moved over the notched end of lever 16. Each of the key bars 15'' and 15''' is provided with a lateral pin 19 which operates in a slot in each of the plates 17 and 18, whereby when these two key bars are operated, the plate 17 or the plate 18 will be rocked forwardly over the end of lever 16 to arrest said lever in its intended position. No stops are operated by the keys 15' or 15'''' to arrest the lever 16 in its predetermined position, for the reason that when bar 15' is operated to position a single zero setting up pin, it is unnecessary to rock the lever 16, and when the bar 15'''' is operated, it will move the lever 16 to the full limit of its movement beyond which bounds, it, and its associated parts, can not be moved. Lever 16 is connected by a link 20 with a bell crank 21, the upwardly extending member of which is pivotally connected by a link 22 to the end of lever 8 which, as before described, carries the flexible escapement pallet 7. Lever 8, in the multiple zero key construction shown in Fig. 6, is slotted at its

pivoted end so that it may be moved longitudinally to place the escapement pallet toward the right the distance of two, three or four teeth, depending upon the multiple zero key which is operated. Instead of having the upper end of bar 6 engaging the pin 9 so that the pallet end of the lever 8 will merely be lifted for a single space escapement, as shown in Fig. 12, I provide a ratchet toothed member 23 on the pin 9 and provide the same with a pin 23' at its opposite or left hand end, as shown in Fig. 7, to which pin is connected the spring 10 heretofore referred to. The upper end of the bar 6, as shown in Fig. 8, is likewise provided with ratchet teeth 6' which coöperate with the ratchet teeth on the lower edge of member 23.

The operation of the parts above described is as follows. When any of the multiple zero key bars 15'', 15''' or 15'''' is operated, the zero setting up pins 93' are first positioned upon the depression of the forward ends of said key bars and simultaneously the lever 16 is rocked so as to operate the bell crank 21 and through the link connection 22 to draw the lever 8 toward the right a distance of two, three or four escapement teeth, depending upon the multiple zero key operated. When the bar 6 rises, it will place the fixed pallet 5 in engagement with an escapement tooth and at the same time lift the movable pallet 7 above the escapement teeth and draw the lever 8 carrying said pallet 7 toward the right two, three or four spaces depending upon the throw of lever 16. When the lever 16 is arrested, or reaches the limit of its throw, depending upon the multiple zero key operated, the ratchet engagement between the upper end of bar 6 and pivoted member 23 will prevent the lever 8 from moving leftwardly until the pallet 7, or the point thereof, is located in front of the escapement tooth two, three, or four steps removed. When the pallet 7 has engaged its proper escapement tooth, it will be arrested against further downward movement under the action of spring 10, but the bar 6 will be drawn downwardly by the spring 12 a slightly further distance until the ratchet teeth 6' have been disengaged from the ratchet teeth on member 23, when the spring connected to the laterally movable carriage will pull the same leftwardly until the end wall of the slot in the pivoted end of lever 8 will engage its pivot pin and arrest the further leftward movement of the carriage. Thus, for a single-step escapement, when bar 15' is operated, the device works substantially the same as the construction shown in Figs. 10 to 12; but when any of the bars 15'', 15''', or 15'''' is operated, the bell crank 21 has imparted thereto a differential throw so as to position the pallet 7 two, three or four teeth removed, the ratchet toothed en-

4
 engagement between the upper end of bar 6 and the pivoted member 23 permitting the lever 8 to be drawn toward the right (Figs. 6 and 7) the requisite distance. When the bell crank 21 reaches the limit of its throw, the ratchet engagement between the upper end of bars 6 and member 23 will maintain the proper relation between the parts, locking lever 8 against leftward movement until 10 the fixed pallet 5 has been withdrawn and the movable pallet 7 properly positioned two or more escapement teeth removed so that the carriage will be pulled leftwardly a corresponding number of spaces.

15 In the multiple key mechanism some means other than the double cam faced restoring bar 68 is necessary to restore the zero setting up pins 63' and this means, as shown in the accompanying drawings, consists of a lever 25 pivoted to a bracket secured to one of the track bars 58. The left hand end of this lever (see Fig. 6) has a spring 26 connected thereto whereby said end is normally held elevated above the 25 zero setting up pins 63'. The right hand end of this lever is provided with an inclined lower edge designed to coöperate with a pin 27 on the traveling carriage. This pin is intended to engage the cam face of lever 30 25 so as to rock said lever and restore all of the pins 63' which may have been positioned in the operation of the machine. It will be remembered that in the construction disclosed in the Belgian patent before mentioned, the traveling carriage 57 has an excess movement to the right beyond its home position and consequently when the carriage returns to a normal position after such excess movement, it will permit the end of 40 lever 25 over the zero setting up pins 63' to be raised above said pins so as to permit subsequent operations thereof. In Fig. 6 I have shown the home position of the carriage and its pin 27 in full lines, the dotted 45 line position of pin 27 indicates the limit of the excess movement of the carriage in which position the pin lies under the flat extreme end of lever 25 so as to hold the opposite end of the lever practically stationary for a 50 short period of time while the zero setting up pins 63' are fully depressed.

I am aware of the patent to Stroh, No. 829,357, dated August 21, 1906, wherein there is disclosed a construction for setting 55 up a plurality of stops by the operation of a single multiple zero key, but my construction differs materially from the structure illustrated in said Stroh patent in providing a mechanism having a variable throw for 60 controlling the position of one of the escapement pallets.

What I claim is:

1. In a machine of the character described, the combination with digit keys and multiple zero keys, setting up pins under control of said keys, and means for setting up a plurality of pins by operation of a single multiple zero key, said means including a differentially movable element and means for controlling the variable throw of said 70 element.

2. The combination with a traveling carriage and its setting up pins, an escapement mechanism for said carriage including fixed and movable pallets, and means for setting 75 up a plurality of pins in the carriage, said means also varying the relation of one set of pallets to the escapement mechanism whereby the carriage may be differentially advanced.

3. The combination with a traveling carriage and its setting up pins, means for advancing the carriage a distance greater than one denomination, said means including an element having a differential throw, and 85 means for simultaneously positioning a number of setting up pins in the carriage corresponding to the differential throw of said advancing means.

4. The combination of a traveling carriage containing setting up pins in longitudinal and transverse series, and key operated means for selectively and simultaneously positioning two or more setting up pins, and escapement mechanism operated by said 95 keys for arresting the advance movement of the carriage proportionate to the number of pins positioned.

5. The combination of a traveling carriage containing setting up pins, multiple 100 zero keys for positioning a selected number of pins, an escapement mechanism for controlling the advance movement of said carriage, and means controlled by said multiple zero keys for displacing a pallet of said 105 escapement mechanism whereby the carriage is permitted to advance a number of spaces corresponding to the number of pins positioned.

6. The combination of a traveling carriage containing setting up pins, and a plate over which the elevated pins pass as the carriage travels, whereby said elevated pins are locked in their raised position.

In testimony whereof I hereunto affix my 115 signature in the presence of two witnesses, this sixth day of July, 1912.

OTTO THIEME.
